UNITED STATES PATENT OFFICE

95,889

DESIGN FOR A VANITY CONTAINER

George H. Beck, Chicago, Ill., assignor to Marion Lambert, Inc., St. Louis, Mo., a corporation of Missouri

Application April 1, 1935, Serial No. 56,142

Term of patent 3½ years

To all whom it may concern:

Be it known that I, George H. Beck, a citizen of the United States, residing at Chicago, county of Cook, State of Illinois, have invented a new, original, and ornamental Design for a Vanity Container, of which the following is a specification, reference being had to the accompanying drawing, forming part thereof.

Fig. 1 is a perspective view of the vanity container looking toward the top showing my new design.

Fig. 2 is a perspective view looking toward the bottom of the vanity container.

I claim:

The ornamental design for a vanity container, substantially as shown.

GEORGE H. BECK.
